UNITED STATES PATENT OFFICE

153,286

DESIGN FOR A SEWING MACHINE

Earl Howard, La Canada, Calif., assignor to
Irving Burke, Los Angeles, Calif.

Application February 16, 1948, Serial No. 144,528

Term of patent 14 years

(Cl. D70—1)

To all whom it may concern:

Be it known that I, Earl Howard, a citizen of the United States, residing at La Canada, in the county of Los Angeles, State of California, have invented a new, original, and ornamental Design for a Sewing Machine, of which the following is a specification, reference being had to the accompanying drawings, forming a part thereof.

Figure 1 is a top plan view of a sewing machine, showing my new design.

Figure 2 is a front elevational view.

Figure 3 is an end elevational view.

Figure 4 is the opposite end elevational view.

I claim:

The ornamental design for a sewing machine, substantially as shown.

EARL HOWARD.
